UNITED STATES PATENT OFFICE.

JOHN B. DEEDS, OF TERRE HAUTE, INDIANA, ASSIGNOR TO ROBERT H. CATLIN, OF SAME PLACE.

METALLIC PACKING-RING.

SPECIFICATION forming part of Letters Patent No. 395,217, dated December 25, 1888.

Application filed February 11, 1888. Serial No. 263,725. (No model.)

To all whom it may concern:

Be it known that I, JOHN B. DEEDS, a citizen of the United States, residing at Terre Haute, in the county of Vigo and State of Indiana, have invented certain new and useful Improvements in Metallic Packing-Rings; and I do hereby declare the following to be a full, clear, and exact description of the invention, such as will enable others skilled in the art to which it appertains to make and use the same.

This invention relates to certain new and useful improvements in valve and piston-rod packing-rings; and it consists, substantially, in such features of construction thereof as will hereinafter be more particularly described.

The object of the invention is to supply a packing-ring of such construction as that no disconnection of the rod is required for its insertion in the stuffing-box; also, to prevent rusting and wearing of the rod, as well as to prevent leakage, all as will more fully hereinafter appear when taken in connection with the accompanying drawings, wherein—

Figure 1 is a longitudinal sectional view of a stuffing-box and gland, together with a valve or piston-rod in elevation, having thereon a packing-ring embodying my invention. Fig. 2 is a diametric section of the ring, showing its form of construction. Fig. 3 is a view in perspective of the two parts or segments of which the ring is constructed.

According to my invention I form the packing ring or sleeve of two parts longitudinally, and in one part I provide openings or recesses adapted to receive small corresponding projecting portions or pins on the other part. One end of the ring is formed $\triangle$ -shaped, while the outer side thereof is straight, so as to furnish surface enough to insure its being kept straight within the box.

Reference being had to the several parts by the letters marked thereon, A represents a stuffing-box, B its gland, and C the valve or piston-rod, all of which are of well-known construction or form, and the workings of which are understood.

D represents as a whole a packing-ring of my present invention, which, as shown, is formed of the two segments or portions hav-

ing the holes or openings 1 1, while the other portion is formed or provided with corresponding lugs or pins, 2 2, adapted to enter such openings, and when the two portions are united in this way it will be seen that in use 55 they will be kept intact and be prevented from slipping apart or away from each other. The outer side of the ring is formed straight, as shown at b, so as to furnish sufficient bearing-surface to maintain the same straight 60 within the stuffing-box. The bore or interior of the ring is formed also with a small straight flange, c, which adapts a better bearing or fitting of the said ring to the rod. One end of the ring is pointed or $\triangle$ -shaped all around, as 65 seen at d, from which construction the packing surrounding the ring will in use be forced to both the rod and the walls of the stuffing-box, as in the manner of being spread apart by a wedge. The other end of the ring is cut 70 away or beveled, as seen at e, and which construction also serves to maintain the surrounding packing against the rod.

Filling the interior of the stuffing-box around the ring D and the rod is a packing 75 compound, say, of hemp, flax, or other equivalent material. In practice, however, I prefer to employ the compound set forth in an application filed of even date herewith, Serial No. 263,674; but I of course am not limited in 80 this case to the use of such material, since I have found many well-known kinds to answer.

Having thus described my invention, what I claim as new, and desire to secure by Letters Patent, is—

In a valve-rod packing, the metallic ring D, constituted of two parts having corresponding openings and pins by which they are held together, one end of said ring being pointed and the other end cut away or beveled, while 90 the outer and inner sides thereof are formed with the straight bearing-surfaces b and c, in combination with a packing compound of textile material, substantially as described.

In testimony whereof I affix my signature in 95 presence of two witnesses.

JOHN B. DEEDS.

Witnesses:

WILLIAM DIDRISH,
JOHN R. TAYLOR.
